CLAIM

The ornamental design for a binder with translucent covers, as shown and described.

DESCRIPTION

FIG. 1 is a top perspective view of a binder with translucent covers showing our new design;

FIG. 2 is a front elevational view thereof, the opposite side elevational view being a mirror image;

FIG. 3 is a top elevational view thereof;

FIG. 4 is a bottom elevational view thereof;

FIG. 5 is a left side elevational view thereof; and,

FIG. 6 is a right side elevational view thereof.

The diagonal shading on the covers represents a translucent material.
